UNITED STATES PATENT OFFICE

2,475,860

ROCKER ARM OIL PASSAGE CLEANSING DEVICE FOR OVERHEAD VALVE ENGINES

Harry S. Stronach, Oak Park, and Edward J. Emmons and James B. Dusil, Berwyn, Ill.; Charles W. Johnson, executor of said Harry S. Stronach, deceased, assignor to said Emmons and said Dusil

Application January 4, 1946, Serial No. 639,066

1 Claim. (Cl. 15—406)

1

Our invention relates to a device for use in cleaning oil conduits which have become clogged or plugged with dirt, solidified particles of oil, sludge, or the like, to such an extent that oil will not flow therethrough, and has particular reference to a device for use in cleaning the oil conduits commonly employed in the rocker arms of overhead valve internal combustion engines.

The primary object of our invention is the provision of a device which, by means of compressed air, can be utilized to blow foreign materials out of oil conduits in the rocker arms of overhead valve internal combustion engines easily and quickly with a minimum amount of time and effort.

Another and further object of our invention is the provision of a device for cleaning out the oil conduits in rocker arms which is so fashioned that it can be easily and quickly applied in position for operation and which when in position can be easily held against displacement so that only a few minutes' time is required for cleaning the oil conduits, which heretofore has necessitated the complete tearing down of the overhead structure and the cleaning of the conduits by hand, requiring several hours of labor to accomplish a satisfactory result.

Another and further object of our invention is the provision of an apparatus which is easy to produce, comparatively cheap to manufacture, and which can be attached to any suitable compressed air source now common and available in nearly all garages where repair work is performed and which renders the work of the mechanic in cleaning out these oil conduits a very easy and efficient task as compared with the methods heretofore followed.

These and other objects of our invention will appear as the description proceeds and will be more fully understood by the accompanying drawings, in which—

Figure 1 is a view, partially in elevation and partially in section, of a portion of a motor showing our invention applied thereto;

Figure 2 is a top plan view of a section of a motor showing the device as it is applied in use; and

Figure 3 is a detailed perspective view of the nozzle attached to the main valve body as used in our invention.

Referring now specifically to the drawings, in which like character references are used to designate like parts, a motor block 10 is shown having brackets 11, 11 secured thereto within which a hollow rocker shaft 12 is mounted, the rocker shaft having ports 13 therein in spaced relation

5 with each other, with rocker arms 14, which have bushings 15 therein, mounted upon the rocker shaft 12. These bushings have circumferentially extending oil grooves 16 therein on their inner periphery with other grooves 17 on the outer periphery, with ports 18 extending through the wall of the portion 15, providing means of communication between the oil grooves 16 and 17. The rocker arm 14, at one of its ends, engages a valve stem 19 with the usual spring 20 and bushing construction 21 being provided, while on the opposite side of the rocker arm a threaded member 22 is provided having a ball end 23 at its lower end operated by the push rod 24 and having a cup member 25 on the end thereof within which the ball end 23 is seated, the push rod 24 leading to the usual cam shaft, by means of which the push rod is reciprocated in raising and lowering the rocker arm to periodically depress the valve located on the lower end of the valve stem, as shown in the drawing, in both the intake and exhaust operations of a motor. An oil passage 26 is provided which extends from the outer upper surface of the rocker 14 in a diagonal direction to the oil groove 17, the purpose of this passage being to allow oil to flow therethrough over the end of the arm 14 toward the valve stem 19 to lubricate this valve stem in its bearing in the motor block. A second oil passage 27 is provided 10 which is diagonally extending through the rocker arm 14 in a direction opposite to the direction of the passage 26, this passage being drilled through the rocker 14 to intercept the opening through which the threaded member 22 extends and into the oil groove 18 with a bisecting passage 28 being provided at right angles to the passage 27 with the metal surrounding the discharge entrance to the passages 28 being cut away to form a funnel-shaped entrance 29 to the passage 28.

40 In the normal oil supply system of overhead internal combustion engines, oil is pumped through the hollow rocker shaft 12, passes out through the ports 13, through the oil grooves 16, through the ports 18, through the oil grooves 17, and out through the passages 26 as heretofore described, and also through the passage 27, which being closed at its outer end by the threaded member 22, the oil is forced out through the passage 28 into the cup 25 and drains downward over the push rod 24, thus lubricating the push rod bearings, the cams, and the like, during the normal operation of the engine.

45 In the operation of motors of this type, the oil passages 26 and 27 are very apt to become clogged with dirt, solidified particles of oil, sludge and the

like, so that the lubrication of the various parts is interrupted. In order to clean these passages heretofore, it has become the practice to completely disassemble the structure heretofore described and clean the passages with an acid bath, or to open these oil passages by inserting a nail, pick, or some other instrument into them to clean them out. This is a long, tedious, and laborious operation, as well as a costly one, and our invention has to do with a comparatively simple device by means of which these passages can be easily and quickly cleaned. Our invention comprises a body member 30 having a valve button 31 on an end of a valve stem 32 which leads to any suitable valve mechanism inside the body 30 and which is secured to a pipe or hose 33 leading to any suitable source of compressed air. In threaded engagement with the opposite end of the body member 30 is a threaded nipple 34 having a wrench piece 35 thereon and a tubular member 36 projecting therefrom of hollow construction which is bent into a U form at the free end with a vertically extending leg 37 of the U form being provided and a transverse portion 38 with another upstanding portion 39 with the end of the tube member being bevelled at 40 which cooperates with the funnel-shaped opening 29 at the discharge end of the oil passage 28. The U-shaped end portion is disposed at a slight angle to the vertical plane through the tube 36 in a direction away from the body 30, this arrangement providing for the easy and quick insertion of the end of the tube into the end of the discharge passage 28.

In the operation of the device, which is best illustrated in Figure 2, the operator places the tube 36 against the side of the arm 14, and by slightly rotating the device in a clockwise direction, can easily and quickly insert the bevelled end 40 into the bevelled discharge portion of the tube 28, and when in this position the operator presses downward on the button 31 which opens the valve in the casing and directs compressed air into the opening 28, 27 through the oil grooves, and out of the oil passage 26, thereby removing any foreign material which is lodged in these pas-

5 sages and quickly and effectively cleaning out these oil passages so they operate properly. This operation takes 15 or 20 minutes against the 3 to 4 hours' time of a mechanic in tearing down, cleaning out, and assembling the various parts of the motor as herein described.

10 While we have shown certain preferred embodiments of our invention, these are to be understood as illustrative only as it is capable of variation to meet differing conditions and requirements, and we contemplate such modifications as come within the spirit and scope of the appended claim.

We claim:

15 A device for cleaning oil passages comprising in combination a casing, a valve in said casing, a detachable tubular member secured to the said casing, having a stem portion and a U-shaped portion at the end thereof, the entire U-shaped portion being integrally formed with the stem and 20 in a plane substantially at right angles to the longitudinal axis of the stem the discharge end of the said U-shaped portion being slightly offset with respect to the plane of the said U-shaped portion in a direction away from the said casing.

25 HARRY S. STRONACH.
